UNITED STATES PATENT OFFICE

2,608,841

DRINKING CUP FOR USE BY INFANTS AND
INVALIDS SUCH AS CHAIR AND BEDRID-
DEN PATIENTS

William W. Rice, Chicago, Ill.

Application November 16, 1950, Serial No. 196,062

2 Claims. (CL. 65—13)

1

My invention relates to certain new and useful improvements in drinking cups for use by infants and invalids such as chair or bedridden patients.

As such the invention has for its object a simplified and improved arrangement for facilitating feeding liquid to the infant or patient and for controlling the flow of fluid from the cup during such feeding and drinking.

My present invention constitutes an improvement over that shown in my pending application Serial No. 103,447, filed July 7, 1949.

One of the principal objects of the invention is to provide a drinking cup especially adapted for use by infants and bedridden patients whereby the flow of fluid may be easily controlled through the simple operation of an arrangement provided for that purpose.

Another object of the invention is to provide such a drinking cup which comprises relatively few parts resulting in the manufacture thereof at an economical cost.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of the invention showing the same in use;

Fig. 2 is an enlarged fragmentary sectional detail view of the cap or cover portion of the cup;

Fig. 3 is a fragmentary view of the fluid control valve showing the same in closed position;

Fig. 4 is a top plan view of the invention; and

Fig. 5 is a fragmentary sectional detail view, similar to that shown in Fig. 3, but showing a modified form of construction.

The preferred form of construction of my invention is shown in the drawings. In such drawings a cup is indicated at 10. This cup may be formed of any suitable material best suited for the purpose and preferably of a material which will withstand breakage, washing or cleansing.

In the present instance this cup at its open end portion is provided with an enlarged collar 11. In this collar 11 is telescoped the flange portion 12 of a cap or cover 13. The telescoping section of the cap 13 is offset with respect to the side walls 14 thereof to provide a shoulder 15, serving to limit the insertion of the cap 13 into the collar 11.

It is preferably desirable that there be frictional engagement between the telescoping por-

tion of the cap and the collar 11. Such an arrangement is desirable so as to prevent accidental removal of the cap from the cup.

The top wall 16 of the cap 13 is provided with an opening 17 through which projects a neck portion 18 of a valve 19. Such valve 19 provides a flange 20 which limits the projection of the neck portion 18 thereof through the opening 17. The valve comprises at the exterior of the cap 13 a knurled knob 21 hollow in construction and provided in its top wall with an opening 22. A partition 23 is formed in the valve 19. In the side walls of the knob 21 above this partition 23, are formed openings 24 which are adapted to register with passages 25 formed in the wall 16.

While I have shown two of such openings and passages, it is obvious that any number of such openings or passages may be provided.

To rotatably secure the valve 19 to the top of the wall 16 I fixedly secure on the neck 18 a retaining collar 26.

The valve 19 is located slightly inwardly from the adjacent side wall of the cap, whereby when the cup is held in the hand in the manner shown in Fig. 1, the index finger of the hand may be placed upon the knob 21 to close the opening 22 thereby to regulate the amount of air to be admitted through the passages 25.

The flange 20 has an index finger 27 formed as a part thereof. When the openings 24 register with the passages 25 this index finger is located in a position designated "Open." On each side of the knob 21 are stop pins 28 carried by the top wall 16. These stop pins 28 cooperate with the index finger 27 to limit the rotation of the valve 19 to a position where the openings 24 are in non-registering position with the passages 25.

Extending upwardly and outwardly from the side of the cap opposite the valve 19 there is provided a nipple 29 having a passage 30 formed therein. This nipple is of a form which is most convenient to the user when such nipple is placed in the mouth.

When the device is used to feed a nursing baby the passage of air through the passages 25 are partially blocked by rotating the valve 19 toward either of the stop pins 28. This allows the nursing baby to regulate the flow of liquid from the cup by sucking the liquid therefrom. If the mother desires to increase the flow of the liquid through the nipple during the feeding of the infant the mother merely opens communication between the openings 24 and the passages 25 by turning the knob. She then regulates the flow

of fluid by placing her finger upon the knob over the opening 22.

When the device is used by a bed or chair-ridden patient, the patient himself may regulate the flow of fluid through the nipple 29.

In Fig. 5, I have illustrated a modified form of construction of a valve for controlling admission of air into the cup. In this connection a neck 18' of a valve 19' is threaded into a socket 20'. The valve provides a valve head 21' which is adapted to engage a valve seat 22' to close passage through the opening 23'. The structure and function of this valve is otherwise similar to that shown in Fig. 2.

As will be apparent from the foregoing description my invention is especially useful in feeding liquid to infants and chair or bedridden patients. As it comprises relatively few parts it can be manufactured at an economical cost. The cap may be separated from the cup by the simple operation of withdrawing the telescoping portion thereof from within the cup. This permits cleansing of the several parts making up my improved drinking cup.

The material from which the parts are made may, if desired, be transparent so that the contents of the cup may be readily observed.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. A drinking cup for the purposes herein set forth comprising a cup portion, a cap for said cup portion including a portion adapted to telescope frictionally into the open end of the cup, a nipple formed integral with the cap at one side thereof and providing a passage communicating with the cup, a rotatable air control valve frictionally carried by the cap at the side thereof opposite the nipple and having an opening formed therethrough adapted to be closed by the index finger of a hand supporting the cup, said valve having passages formed in its side walls and communicating with said opening, said top wall of the cap having a passage formed therein communicating with said opening of the valve.

through said valve passages, said telescoping portion of said cap being offset with respect to the side walls thereof to provide a shoulder limiting the insertion of said portion into said cup.

5 2. A drinking cup for the purposes herein set forth comprising a cup portion, a cap for said cup portion including a portion adapted to telescope frictionally into the open end of the cup, a nipple formed integral with the cap at one side thereof and providing a passage communicating with the cup, a rotatable air control valve frictionally carried by the cap at the side thereof opposite the nipple and having an opening formed therethrough adapted to be closed by the index finger of a hand supporting the cup, said valve having passages formed in its side walls and communicating with said opening, said top wall of the cap having a passage formed therein communicating with said opening of the valve through said valve passages, said valve including a knob portion exterior of the cap to facilitate rotating the valve to disposed the valve passages from or in closed position with respect to said cap passage, means for limiting said rotation of said valve, said telescoping portion of said cap being offset with respect to the side walls thereof to provide a shoulder limiting the insertion of said portion into said cup.
